US0D1061851S

(12) **United States Design Patent** (10) **Patent No.:** **US D1,061,851 S**
(45) **Date of Patent:** **** Feb. 11, 2025**

(54) **FAN**

(71) Applicant: **Vornado Air, LLC**, Andover, KS (US)

(72) Inventors: **Byron Loibl**, Wichita, KS (US);
Gregory Pease, Andover, KS (US);
Brian Cartwright, Wichita, KS (US);
Anthony Fischer, Wichita, KS (US);
Joshua Ayala, Maize, KS (US)

(73) Assignee: **Vornado Air, LLC**, Andover, KS (US)

(**) Term: **15 Years**

(21) Appl. No.: **29/895,133**

(22) Filed: **Jun. 16, 2023**

(51) **LOC (15) Cl.** **23-04**

(52) **U.S. Cl.**

USPC **D23/378**

(58) **Field of Classification Search**

USPC D23/332, 333, 335–337, 364, 370, 378,
D23/411–412

CPC ... F04D 29/005; F04D 25/0673; F04D 25/166

(57) **CLAIM**

The ornamental design for a fan, as shown and described.

DESCRIPTION

FIG. 1 is a front top perspective view of the fan of the present design.

FIG. 2 is a rear bottom perspective view of the fan of the present design.

FIG. 3 is an elevation view of the front, right side of the fan of FIG. 1.

FIG. 4 is an elevation view of the rear, left side of the fan of FIG. 1.

FIG. 5 is an elevation view of the rear, right side of the fan of FIG. 1.

FIG. 6 is an elevation view of the front, left side of the fan of FIG. 1.

FIG. 7 is a top plan view of the fan of FIG. 1; and,

FIG. 8 is a bottom plan view of the fan of FIG. 1.

In the drawings, the broken lines depict portions of the fan that form no part of the claimed design.

1 Claim, 7 Drawing Sheets
